UNITED STATES PATENT OFFICE

MICHEL D. BUIVID, OF STRATFORD, CONNECTICUT

ADVERTISING DEVICE

Application filed March 1, 1932. Serial No. 596,110.

This invention relates to an advertising device and more particularly to an advertising device which is adapted to be associated with the hand grip or hand strap commonly used in public carriers and the like.

In advertising in public carriers, such as subways, street cars, buses and the like, the advertising matter is generally placed on the side walls of the carriers and when the carrier is crowded it is necessary for the passengers to stand in the aisles and brace themselves from falling by means of hand grips which are suspended on straps which encircle a supporting bar running generally longitudinally of the subway car or other carrier. The positioning of the supporting bar and hand grip directly in front of the advertising matter obstructs the view thereof and decreases its advertising value.

It is one of the objects of this invention to provide for the display of advertising matter on the hand grips which are commonly employed in common carriers.

Another object of the invention is to provide an attaching device in which the advertising matter is inserted which may be associated with any type of hand grip or hand support which is generally used in public carriers.

Another object of the invention is to provide an attaching device of this character in which upon the swinging movement of the suspended handle there will be effected a change in the advertising matter displayed.

These and other objects of the invention will become apparent during the course of the following description.

The invention contemplates the provision of an attaching device which is adapted to be secured to the handle supporting member which is provided with a pair or any number of spaced slots through which there is adapted to be inserted a plate having advertising matter thereon and which is securely fastened to the supporting rod so that upon the rotating movement of the supporting handle the advertising matter is displayed in a novel manner. The invention also contemplates the provision of the attaching member being provided with a plurality of spaced

slots through which the advertising matter may be seen in different phraseology and the like. The advertising value of the device resides in the particular and novel means of attaching the same on the hand grip or support for the reason that the eye is naturally and instinctively cast in that particular direction when one reaches for the grip with the hand and the thing that attracts the eye of the passenger at that particular moment is the advertising matter on the hand grip.

The invention also contemplates the provision of a mirror or the like to be secured to the attaching member so that ladies or gentlemen passengers may attend to their personal appearances while being conveyed to their destination. Furthermore, the passenger in using the mirror must necessarily focus his attention in the direction of the advertising matter.

In the accompanying drawings forming a part of this application and in which like numerals are employed to designate like parts throughout the same,

Figure 1 is a vertical sectional view of the device illustrating the manner in which it is attached to the hand support,

Figure 2 is a front elevational view illustrating the manner in which an advertising card is inserted in the attaching box and showing the advertising matter on the plate registering with the slot in the advertising card,

Figure 3 is a perspective view of the attaching box,

Figure 4 is a front elevational view of the advertising plate showing an advertising card in position in the plate,

Figure 5 is a perspective view of the advertising plate, illustrating its extended strap portion which is secured to the handle supporting rod of public carrier,

Figure 6 is a top plan view partly in section illustrating the manner in which the handle supporting member is secured to the support,

Figure 7 is a horizontal sectional view of Figure 1, taken on line 7—7,

Figure 8 is a perspective view of the strap

employed to connect the advertising plate to the supporting rod, and

Figure 9 is a sectional view of an advertising card illustrating the manner in which 5 a mirror may be secured to the advertising card.

In the drawings, wherein for the purpose of illustration is shown a preferred embodiment of the invention, the numeral 10 generally designates a supporting rod on which the supporting strap hangers 12 carrying the handles are mounted. These supporting rods are generally arranged longitudinally of the public carrier and the handle 15 supporting straps are arranged spacedly on the supporting rod. The handle supporting member 12 encircles the supporting rod and has interposed therebetween a coil spring one end of which engages the encircling portion of the strap and the other end of which 20 engages a pin 18 of the rod so as to maintain the supporting strap in a vertical position. It is to be noted in this connection that there is shown only one form of supporting strap 25 and that the invention is not limited to being attached to this particular form of strap, inasmuch as the same may be generally modified to fit any type of strap now in general use. On the lower end of the strap hanger 30 there is provided a handle grip 20 which is secured to the strap by means of the screw bolt 22, or the like.

An attaching box 24 having its sides and 35 lower end portions bent over is secured to the flange portion 26 of the supporting strap by means of the outwardly extended flange portions 28 which are formed by cutting the advertising box and bending the 40 same outwardly. The flange portions 28 of the advertising box are secured to the flange 26 of the handle supporting member 30.

The inwardly bent sides and lower edges of the attaching box not only provide a 45 means of retaining an advertising card in the attaching box but they also add additional strength to the attaching box itself. As illustrated in Figure 3 at substantially the midsection of the attaching box, spaced 50 grooves 34 and 36 are cut therein and the edges and portions between the grooves are cut outwardly defining a passageway for the rectangular-shaped advertising plate 38. The advertising plate 38 is likewise provided 55 with inwardly bent side and lower edge portions 40 defining a pocket or the like for an advertising card.

The upper portion of the advertising plate merges into a tongue portion 42 which at its 60 terminal end, is provided with a pair of spaced apertures 46 which are adapted to be secured by means of screw threaded bolts, rivets or the like 44, to a strap 48 which is spaced from and saddles the upper portion 65 of the hanger 14. The strap is secured to

the rod 10 by means of screws or bolts 51, or the like.

As is clearly indicated in Figures 1 and 7, the tongue portion 42 of the advertising plate is trained around the upper circular portion 70 of the supports 14 and passes through the upper slots 34 in the advertising box and through the lower slot 36 of the advertising box so that upon a rotating movement of the support 14, by means of the handle 20 there is a movement of the advertising box 24 with respect to the advertising plate 38 to the end that any advertising material which is arranged on the outer surface of the advertising plate will be clearly shown to any one disposed in front of the advertising box. 75

Normally the engagement of the spring 16 encircling the supporting rod and engaging the hanger 14 causes the hanger to assume a downward, vertical position and when a card having advertising material thereon, such as is illustrated in Figure 4, is arranged in the box portion defined by the inwardly bent edges of the advertising plate, the advertising material is clearly visible to either the 80 passenger being supported by the hanger, or to any of the other passengers which are seated in an opposite direction thereto. 85

As illustrated in Figures 2 and 4, the advertising plate 38 may have inserted therein an advertising card on which different words or slogans may be arranged. In the particular case shown the words "Use for long ruby wear" are for the purpose of illustration. An advertising card having an advertising matter on its upper portion and a pair of spaced slots or openings is inserted in the advertising box 24. When the strap hanger is in its normal angular position the words "Use", "Ruby" register respectively with the openings and in combination with the other advertising matter on the card in the advertising box, advertise the particular brand of lipstick. 90

Upon a rotating movement of the strap hanger the words "For long wear" register with the openings to the end that different advertising matter and slogans may be brought to the attention of the observer. 100

As is illustrated in Figures 2 and 9, a mirror may be secured to the lower portion or any other portion of the advertising card 50 either by, as illustrated in Fig. 9, extending the edges 52 of the frame of the mirror through the card and bending the same against the back of the card, or if so desired by attaching the back of the mirror to the front portion of the card. 110

In this connection, it is to be noted that the placing of a mirror on the advertising card, as illustrated in Figure 2, has a two-fold purpose; first, in that it provides for gentlemen, as well as lady passengers, a means of enabling them to correct their dressing apparel or appearance, and at the same time provide 125 130

an attaching medium which will cause them to focus their attention on the associated advertising matter on the card.

It will thus be seen that the particular arrangement provides a means for the insertion of cards having any type of advertising matter thereon and that the same may be easily withdrawn or inserted without any difficulty.

There is provided in the advertising box 10 24, at the upper edge thereof, a cut-out portion 56 to enable the advertising cards to be conveniently removed.

The invention is not limited to the movable type since it is obvious that if it is so desired 15 by not placing advertising matter in the plate 38 and not making use of the slots 34 and 36 a non-movable advertising card may be positioned in the holder 24.

The invention forming the subject of this 20 application is capable of a wide variety of modifications, and expressions, without departing from the spirit and scope thereof. For example, the invention is not intended to be limited to the particular type of strap 25 hanger, nor to the particular means of maintaining the advertising matter in the advertising strap or plate or the particular method illustrating the means for attaching the device to the strap hanger. Likewise, any 30 shape of advertising box may be employed as well as any particular kind of advertising material and thus, it is to be understood that the form of invention herewith shown and described is to be taken merely as a preferred 35 example of the same and that such minor changes in arrangement and construction of parts may be made as will remain within the spirit of the invention and the scope of the appended claims.

40 Having thus described the invention what is claimed is:

1. The combination with a fixed support and a strap hanger rotatably supported thereon, of an advertising device comprising 45 a holder rigidly secured to said strap hanger, and a plate slidably supported by said holder and bearing advertising matter, said plate having an extension secured to said fixed support whereby rotation of said hanger will slidably move said holder with respect to said plate.

2. The combination with a fixed support and a strap hanger rotatably supported thereon, of an advertising device including a 55 holder having attaching means secured to said strap, a plate bearing advertising matter slidably carried by said holder and having an extension fixedly secured to said support whereby rotation of said strap will slidably move said holder with respect to said plate, and a cover plate carried by said holder and disposed over said first named plate, said cover plate being provided with sight 60 openings through which the advertising matter on said first named plate may be viewed.

3. The combination with a fixed support and a strap hanger rotatably supported thereon, of an advertising device comprising a holder rigidly secured to said strap hanger, 70 said holder being provided with a pair of spaced transversely extending slots and a plate bearing advertising matter slidably supported by said holder and movable through said slots, said plate having an extension secured to said fixed support, whereby rotation of said hanger will slidably move said holder with respect to said plate.

4. The combination with a fixed support and a strap hanger rotatably supported thereon of an advertising device comprising 75 a holder rigidly secured to said strap hanger, a plate slidably supported by said holder and bearing advertising matter, said plate having an extension secured to said fixed support whereby rotation of said hanger will 80 slidably move said holder with respect to said plate, and resilient means associated with said fixed support and said strap hanger for normally maintaining said strap hanger in a substantially vertical position.

In testimony whereof I affix my signature.

MICHEL D. BUIVID.
